Primary Examiner — April Rivas

CLAIM

The ornamental design for a combination game backpack and detachable cooler, as shown and described.

DESCRIPTION

FIG. 1 is a front elevational view of a combination game backpack and detachable cooler;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof;

FIG. 7 is a front perspective view thereof;

FIG. 8 is a rear perspective view thereof;

FIG. 9 is a front elevational view of a combination game backpack and detachable cooler, showing the cooler detached with the top open and the game backpack with an open front pocket;

FIG. 10 is a right side elevational view thereof;

FIG. 11 is a rear elevational view thereof;

FIG. 12 is a left side elevational view thereof;

FIG. 13 is a top plan view thereof;

FIG. 14 is a bottom plan view thereof;

FIG. 15 is a front perspective view thereof; and,

FIG. 16 is a rear perspective view thereof.
